The ornamental design for a soap dispenser, as shown and described.

DESCRIPTION

FIG. 1 is a front view of a soap dispenser incorporating the preferred embodiment of the invention;

FIG. 2 is a bottom view of the dispenser;

FIG. 3 is a top view of the dispenser; and,

FIG. 4 is a left side view of the dispenser, with the right side view being symmetrical.

The back of the dispenser is plain and unornamented.
